HIS ATTORNEY

UNITED STATES PATENT OFFICE.

WILLIAM H. HARDIN, OF NEW YORK, N. Y.

DESIGN FOR AN ADVERTISING-FRAME.

SPECIFICATION forming part of Design No. 18,955, dated March 12, 1889.

Application filed January 29, 1889. Serial No. 298,033. Term of patent 7 years.

To all whom it may concern:

Be it known that I, WILLIAM H. HARDIN, a citizen of the United States, residing at New York, in the county and State of New York, have invented a certain new and Ornamental Design in Advertising-Frames; and I do declare the following to be a full, clear, and exact description of the invention, such as will enable others skilled in the art to which it applies to make and use the same, reference being had to the accompanying drawing, and to the letters and figures marked thereon, which form part of this specification.

My design consists of a frame divided by moldings or in any approved manner into the pattern shown by the accompanying drawing.

My design consists of an exterior square divided into spaces by means of straight lines. Eight of these lines a, b, c, c', d, d', e , and e' are parallel with one of the sides of the square and with each other, two of them, a and b , completely cross the square, four of them, c, c', d , and d' , terminate in the sides of an interior square, 17, which are parallel to the diagonals of the exterior square, and the other two, e and e' , are coincident with a medial line of the outer square and a diagonal of the inner square and terminate in the corners of the latter. Six of the lines, f, f', g, g', h , and h' , are

parallel to the other sides of the square and to each other, f, g , and h terminating in a , and f', g' , and h' terminating in b , the lines h and h' coinciding with the other medial line of the outer square and the diagonal of the inner square. Four other lines, terminating in a, b, e , and e' and parallel to the diagonals of the outer square, constitute the sides of the inner square. These lines divide the space of the exterior square into four corner rectangles, 1, 4, 13, and 16, four other rectangles of equal area, 2, 3, 14, and 15, four trapezoids, 5, 6, 11, and 12, of equal area, and four other trapezoids, 7, 8, 9, and 10, also of equal area, and the interior square 17.

What I claim as new is—

The design for an advertising-frame, consisting of an exterior square divided into a central square, 17, four corner rectangles, 1, 4, 13, and 16, four rectangles, 2, 3, 14, and 15, and eight trapezoids, 5, 6, 7, 8, 9, 10, 11, and 12, as shown and described.

In testimony whereof I affix my signature in presence of two witnesses.

WILLIAM H. HARDIN.
